ARMAND H. PEYCKE, OF CHICAGO, ILLINOIS, AND LOREN L. WHITNEY, OF HAMMOND, INDIANA, ASSIGNEES TO AMERICAN STEEL FOUNDRIES, OF CHICAGO, ILLINOIS, A CORPORATION OF NEW JERSEY.

BRAKE-SUPPORTING MECHANISM.

1,322,047.

Specification of Letters Patent.

Patented Nov. 18, 1919.

Application filed February 13, 1918. Serial No. 216,956.

To all whom it may concern:

Be it known that we, ARMAND H. PEYCKE and LOREN L. WHITNEY, citizens of the United States, and residents, respectively, 5 of Chicago, in the county of Cook and State of Illinois, and of Hammond, in the county of Lake and State of Indiana, have invented certain new and useful Improvements in Brake-Supporting Mechanism, of which the 10 following is a specification.

This invention relates to brake supporting mechanism.

It has for its object to level or support the 15 brake beam in a simple and effective manner 5 to meet the various requirements for successful commercial operation.

This and other objects are accomplished, generally speaking, by providing, in combination, a brake beam, a safety bar therefor, 20 and a bracket supported by the safety bar and having a relatively sliding connection with the beam.

The invention is illustrated on the accompanying sheet of drawings, in which— 25 Figure 1 is a fragmentary side elevation of a railway car truck embodying our invention;

Fig. 2 is an enlarged side elevation, parts being in section, of a portion of the arrangement shown in Fig. 1; and,

Fig. 3 is a fragmentary plan view of part of the arrangement shown in Fig. 2.

The various novel features of our invention will be apparent from the following description and drawings and will be particularly pointed out in the appended claims.

Referring to the drawings, it will be noted that we have disclosed a railway car truck, including a spring plank 10, to which are 40 connected hangers 11 which support a horizontally extending rigid safety bar 12, the ends of which underlie brake beams 13 for the purpose of preventing such brake beams accidentally falling to the tracks in the 45 event that the brake beams are severed from their normal hangings. In order to prevent the tension rod 14 of the brake beam from sagging downwardly, we have provided means for leveling or supporting the brake beam, and especially the tension rod 14 thereof. This means takes the form of a 50 spring bracket or arm 15 of general Z-shape (see Fig. 2), one end 16 of which arm is secured in a supporting member 17, which 55 preferably fits over and is connected to the

safety bar 12 near the ends thereof. If desired, the support may be longitudinally adjustably connected to the safety rod and longitudinally applied thereto and removable therefrom. The outer free end 18 of the 60 Z-shaped bracket or arm 15 is arranged preferably in a horizontal plane and underlies the tension rod 14 for supporting the latter, not only when it is at rest, but also during movements of the brake beam when 65 the same are applied and released. The bracket member or arm 15, which preferably is of spring material, extends upwardly, inwardly and forwardly from the safety bar 12 toward the associated wheels of the truck. 70 By means of this arrangement the safety bar not only performs its function of preventing the brake beam accidentally from falling to the track when disconnected from its normal hangings, but also the brake beams 75 are supported in proper position to accomplish satisfactory braking results.

It is our intention to cover any modifications of the invention falling within the spirit and scope of the following claims. 80

We claim:

1. In combination, a brake beam, a safety bar therefor, a bracket connected to the safety bar for longitudinal adjustment thereon and having a horizontally extending portion for supporting the brake beam. 85

2. In combination, a brake beam, a safety bar therefor, and a bracket member connected to the safety bar for longitudinal adjustment thereon and extending inwardly 90 therefrom to slidably receive the brake beam for supporting the latter.

3. In combination, a brake beam having a tension member, a safety bar underlying said brake beam, and a bracket extending 95 laterally inward from the safety bar and having a portion upon which the tension member of the beam may be slidably supported.

4. In combination, a brake beam, a rigid 100 safety bar underlying the same, and a Z-shaped bracket supported by said safety bar and having a portion thereof extending laterally inward from the safety bar for normally supporting the brake beam. 105

Signed at Chicago, Illinois, this 2nd day of February, 1918.

ARMAND H. PEYCKE.
LOREN L. WHITNEY.
